FOREIGN PATENT DOCUMENTS

GB 2432290 A 5/2007

Primary Examiner — Lauren R Calve(74) *Attorney, Agent, or Firm* — McKee, Voorhees & Sease, PLC(57) **CLAIM**

We claim the ornamental design for a handle, substantially as shown and described.

DESCRIPTION

FIG. 1 is a top perspective view of a handle.

FIG. 2 is a bottom perspective view of the handle.

FIG. 3 is a bottom end view of the handle.

FIG. 4 is a side elevation view of the handle.

FIG. 5 is a top plan view of the handle; and,

FIG. 6 is a bottom plan view of the handle.
